J. W. DOBLE

APPARATUS FOR CONTROLLING THE FLOW OF LIQUIDS

Filed April 10, 1918

UNITED STATES PATENT OFFICE.

JESSE WARREN DOBLE, OF SAN FRANCISCO, CALIFORNIA, ASSIGNOR TO DOBLE LABORATORIES, OF SAN FRANCISCO, CALIFORNIA, A CORPORATION OF CALIFORNIA.

APPARATUS FOR CONTROLLING THE FLOW OF LIQUIDS.

Application filed April 10, 1918. Serial No. 227,787.

To all whom it may concern:

Be it known that I, JESSE WARREN DOBLE, a citizen of the United States, and a resident of the city and county of San Francisco, State of California, have invented certain new and useful Apparatus for Controlling the Flow of Liquids, of which the following is a specification.

The invention relates to apparatus for controlling the flow of liquids and particularly to the control of liquids being pumped. The invention has particular application in controlling the feed of water to steam generators by variation in conditions within the steam generator or other heat absorbing medium containing apparatus.

An object of the invention is to provide means for controlling the pumping of liquid into a container in accordance with variations in conditions within the container.

Another object of the invention is to provide means for stopping and starting the pumping of water into a water heater or steam generator when the temperature therein reaches certain predetermined minimum and maximum limits.

The invention possesses other advantageous features, some of which, with the foregoing, will be set forth at length in the following description, where I shall outline in full, that form of the invention which I have selected for illustration in the drawings accompanying and forming part of the present specification. In said drawings I have shown one form and one application of my invention, but it is to be understood that I do not limit myself to such form or application, since the invention, as set forth in the claims, may be embodied in a plurality of forms and applications.

Referring to said drawings:

Figure 1 is a diagrammatic representation of the application of my invention to a steam generator.

Figure 2 is a longitudinal section through the pump of my invention.

The pump of my invention comprises a pump body 2 having a pump chamber 3 therein into which the piston 4 reciprocates. The chamber 3 is provided with an outlet port 5, preferably arranged at the upper part of the chamber, and the flow of liquid into the pump chamber through this port is prevented by a suitable check valve, such as the ball 6. Liquid is drawn into the pump

chamber from the supply tank 7 or other source of the supply, through the port 8. The inflowing liquid passage is provided with a vertically disposed portion 9 which opens into the port 8 and the flow of liquid through the passage 9 is controlled by the valve 12, arranged to seat on the upper end of the passage 9. The valve 12 normally acts as a check valve which is open on the suction stroke of the piston and closed on the pumping stroke.

The valve 12 is provided with a stem 13 on its upper face which is guided in the cap 14 and with a depending stem 15 which is preferably provided with an enlarged portion 16 on its lower end. The weight of the valve and the stems is ordinarily sufficient to cause the valve to seat and prevent a reverse flow of liquid. Surrounding the enlarged portion 16 of the stem 15 is a solenoid 17 which controls the position or operation of the suction valve 12. The solenoid is preferably arranged so that when it is energized the suction valve is held from its seat, but it may also be arranged to hold the valve to its seat. When the valve is held in either of these positions the pump is inoperative.

In Figure 1 I have shown the pump connected to a steam generator and serving to feed water to the generator. The solenoid circuit is connected to temperature actuated means within the generator, so that the operation of the suction valve is controlled by variations in temperature conditions within the generator. Arranged in the solenoid circuit is a normally open switch 18, one contact of which is carried by the flexed element 19. Bearing against and flexing the element is a lever 21, fulcrumed on a fixed support and pivoted to an expansible rod 22 arranged in the generator. As the temperature in the generator decreases, the length of the rod is lessened and the pressure on the flexible element is lessened, allowing it to straighten out and move the switch contacts toward each other. When a predetermined low temperature is reached, the switch closes, energizing the solenoid and holding the suction valve in position to prevent the pumping of water into the generator. When the temperature in the generator subsequently rises, the solenoid circuit is opened and the suction valve restored to its normal operative condition. The

pump piston is continuously reciprocated, but acts to pump water only when the suction valve is in its normal operative condition.

5. I claim:

1. In combination, a pump, a steam generator arranged to be supplied with liquid from the pump, means for rendering the pump operative and inoperative to pump liquid, and means for controlling the temperature within the generator, comprising means responsive to temperature changes in the steam generator for controlling the means for rendering the pump operative and inoperative.
10. In combination, a pump, a steam generator arranged to be supplied with liquid from the pump, means interposed between the pump and the generator for controlling the flow of liquid to the generator from the pump, said means being arranged to render the pump operative and inoperative to pump liquid, electromagnetic means for controlling said latter means, and means
20. for controlling the temperature within the generator, comprising means responsive to temperature changes in the steam generator for controlling the operation of said electromagnetic means.
25. An apparatus for controlling the temperature within a steam generator comprising means for introducing a liquid into the generator, characterized by the fact that the means is rendered active or inactive to supply liquid solely by variations in the temperature of the steam whereby this temperature is kept within definite limits.
30. In an apparatus for controlling the temperature within a steam generator, means for introducing a liquid into the generator, and means controlling the latter means arranged to permit the entry of liquid at a definite temperature existing in the generator and to prevent entry of the liquid at a lower temperature.
35. In an apparatus for controlling the temperature within a steam generator, a

continuously operated pump for introducing liquid into the generator, an inlet for the pump having a valve member that is arranged to be operated by the pump on its suction stroke to permit liquid to enter the pump, and means responsive to temperature changes within the generator for independently operating said member for disabling the pump.

6. An apparatus for controlling the temperature within a steam generator comprising a pump for introducing a liquid into the generator, and an inlet valve for the pump, characterized by the fact that the valve is operated by variations in the temperature of the steam whereby this temperature is kept within definite limits.

7. In an apparatus for controlling the temperature within a steam generator, a continuously operated pump for introducing liquid into the generator, an inlet for the pump having a valve member that is arranged to be operated by the pump on its suction stroke to permit liquid to enter the pump, electromagnetic means for independently operating said member for disabling the pump, and means responsive to temperature changes within the generator for controlling said electromagnetic means.

8. In an apparatus for controlling the temperature within a steam generator, a pump for introducing liquid into the generator, an inlet valve for the pump, an electromagnet for operating the valve, and means for permitting the entry of liquid to the generator at a definite temperature and to prevent entry of liquid at a lower temperature, comprising means responsive to temperature within the generator for energizing the electromagnet.

In testimony whereof, I have hereunto set my hand at San Francisco, California, this 29 day of March, 1918.

JESSE WARREN DOBLE.

In presence of—

J. B. GARDNER.
